DESIGN FOR A SHOE

Mabel Julianelli and Charles A. Julianelli,
New York, N. Y.

Application June 22, 1946, Serial No. 130,937

Term of patent 3½ years

(C. D7—7)

To all whom it may concern:

Be it known that we, Mabel Julianelli and Charles A. Julianelli, citizens of the United States of America, residing in city of New York, county of New York, and State of New York, have invented a new, original, and ornamental Design for a Shoe, of which the following is a specification, reference being had to the accompanying drawing, forming part thereof.

The figure on the drawing is a front perspective view of a shoe showing our new design. The opposite side presents substantially the same appearance as the side shown in the drawing.

We claim:

The ornamental design for a shoe, substantially as shown and described.

MABEL JULIANELLI.
CHARLES A. JULIANELLI.
